(57) **CLAIM**

The ornamental design for a ceiling panel, as shown and described.

DESCRIPTION

FIG. 1 is a perspective view of a first embodiment of a ceiling panel in accordance with the present invention; FIG. 2 is a first side view of the ceiling panel of FIG. 1; FIG. 3 is a second view of the ceiling panel of FIGS. 1 and 2;

FIG. 4 is a first end view of the ceiling panel of FIGS. 1-3; FIG. 5 is a second end view of the ceiling panel of FIGS. 1-4;

FIG. 6 is a bottom view of the ceiling panel of FIGS. 1-5 with the curtain portion omitted;

FIG. 7 is a perspective view of a second embodiment of a ceiling panel in accordance with the present invention;

FIG. 8 is a first side view of the ceiling panel of FIG. 7; FIG. 9 is a second view of the ceiling panel of FIGS. 7 and 8;

FIG. 10 is a first end view of the ceiling panel of FIGS. 7-9; FIG. 11 is a second end view of the ceiling panel of FIGS. 7-10;

FIG. 12 is a bottom view of the ceiling panel of FIGS. 7-11 with the curtain portion omitted;

FIG. 13 is a perspective view of a third embodiment of a ceiling panel in accordance with the present invention;

FIG. 14 is a first side view of the ceiling panel of FIG. 13; FIG. 15 is a second view of the ceiling panel of FIGS. 13 and 14;

FIG. 16 is a first end view of the ceiling panel of FIGS. 13-15;

FIG. 17 is a second end view of the ceiling panel of FIGS. 13-16;

FIG. 18 is a bottom view of the ceiling panel of FIGS. 13-17 with the curtain portion omitted;

FIG. 19 is a perspective view of a fourth embodiment of a ceiling panel in accordance with the present invention;

FIG. 20 is a first side view of the ceiling panel of FIG. 19;

(Continued)

FIG. 21 is a second view of the ceiling panel of FIGS. 19 and 20;

FIG. 22 is a first end view of the ceiling panel of FIGS. 19-21;

FIG. 23 is a second end view of the ceiling panel of FIGS. 19-22; and,

FIG. 24 is a bottom view of the ceiling panel of FIGS. 19-23 with the curtain portion omitted.
